UNITED STATES PATENT OFFICE.

HARRY HYATT AND JOHN MCGEORGE, OF CLEVELAND, OHIO, ASSIGNORS
TO THE WELLMAN SEAVER ENGINEERING COMPANY, OF CLEVELAND,
OHIO, A CORPORATION OF OHIO.

REVERSING-VALVE FOR REGENERATIVE GAS-FURNACES.

SPECIFICATION forming part of Letters Patent No. 698,283, dated April 22, 1902.

Application filed December 19, 1900. Serial No. 40,375. (No model.)

To all whom it may concern:

Be it known that we, HARRY HYATT and JOHN MCGEORGE, citizens of the United States, and residents of Cleveland, Ohio, have 5 invented certain Improvements in Reversing-Valves for Regenerative Gas-Furnaces, of which the following is a specification.

The object of our invention is to provide a simple and effective form of reversing-valve 10 for use in connection with regenerative furnaces in which gases of very high temperature are employed, the improved valve having been devised with especial reference to properly resisting the destructive effect of 15 such highly-heated gases.

In the accompanying drawings, Figure 1 is a vertical sectional view of part of the flue structure of a regenerative furnace, showing our improved valve applied thereto. Fig. 2 20 is a plan view of the flue end structure to which the valve is adapted. Fig. 3 is an inverted plan view of the valve. Fig. 4 is a view, partly in elevation and partly in vertical section, on the line *a a*, Fig. 1; and Fig. 25 5 is a diagram illustrative of the construction of the automatic valve-turning device forming part of our invention.

In Fig. 2 of the drawings, 1 represents a flue communicating with one regenerator, 2 30 a flue communicating with another regenerator, and 3 and 4 flues to be connected to the regenerators alternately—for instance, flue 3 may be a flue for supplying gas, air, or products of combustion to the regenerators, and 35 flue 4 may be a flue for conveying gas, air, or products of combustion from said regenerators—all four flues terminating in a closely-grouped series of ports 1^a, 2^a, 3^a, and 4^a, respectively occupying the four corners of a 40 quadrangle. The valve used in connection with these ports is in the form of a bell, with two arched or semicircular passages 5 and 6 disposed side by side, so that when the bell is disposed in such manner that the passage 45 5 connects the ports 1^a and 3^a and the passage 6 connects the ports 2^a and 4^a the inlet-flow will be to the regenerator communicating with the flue 1 and the outlet-flow from

the regenerator communicating with the flue 2; but if the bell is turned one-quarter way 50 around, so that its passage 5 provides communication between the ports 1^a and 4^a and its passage 6 provides communication between the ports 2^a and 3^a, the conditions will be reversed, the inlet-flow being now directed 55 to the regenerator communicating with the flue 2 and the outlet-flow being from the regenerator communicating with the flue 1, the original conditions being restored by turning the valve either backward or forward again 60 to the extent of a quarter-turn.

The flue-ports are surrounded and separated by a water-seal chamber 7, terminating in a deeper circular pit 8, and the under side of the bell has a depending outer annular 65 flange 9 for entering the circular pit 8 and other and shallower transverse flanges 10 surrounding the flue-ports and adapted to the sealing-chamber 7, so as to prevent leakage beneath the valve from one passage of the 70 same to the other.

We so construct the valve that it can be completely lined with fire-brick or other refractory material, and thus enabled to withstand the destructive effect of the highly-heated gases employed in modern metallurgical furnaces. 75

The sheet-metal casing 11 of the valve is preferably in the form of a semicylinder, and to the edge of this casing on the open side 80 of the semicylinder are secured the bottom plates 12 of the valve, which serve the double purpose of carrying the sealing-flanges 9 and 10 and forming ledges for the support of the fire-brick lining 13, transverse partition 85 14, and arched blocks 15 of the valve.

All of the portions of the valve which come into contact with the heated gases are thus composed of fire-brick or other refractory material capable of resisting the destructive effect of said gases, all of the metallic portions of the bell being effectively protected from the heat. 90

In order to effect the manipulation of the bell, we prefer to suspend the same by means 95 of a frame 16 from the piston 17 of a power-

cylinder 18, mounted upon a suitable framework 19 above the bell, so that when it is desired to reverse the valve the same can be lifted until its depending flanges 10 are free 5 from the sealing-chamber and can then be partially turned and again lowered after it has reached its new position, the deep annular sealing-flange 9 remaining partially immersed, so as to prevent the complete unsealing 10 of the valve during the reversing operation, and the annular form of the flange and sealing-pit restricting the latter to the smallest possible dimensions.

We prefer to effect the partial rotation of 15 the valve automatically as it is raised and lowered and for this purpose employ a rod 20 and the cylindrical casing 21. This casing has in its sides four vertical grooves or slots 25, the top of each of these being connected 20 to the bottom of the next adjacent by an inclined groove 22, there thus being formed around the interior of the casing a continuous groove. A pin 24, projecting laterally from the rod 20, enters and slides in this 25 groove, there being pivoted spring-pieces 23 placed therein and acting as pawls to insure a forward revolution of the rod 20 each time the bell is raised.

In operation when the bell is moved upwardly the pin 24 is made to follow the inclined groove 22 and as a result causes the rod 20, with the attached parts, to make a quarter-revolution. As the bell is lowered the pin follows the vertical groove 25 to the bottom thereof, the pin being guided into said groove by the switch or ratchet and is now ready to enter the next inclined groove, when the bell is again raised.

Having thus described our invention, we 40 claim and desire to secure by Letters Patent—

1. A reversing-valve for regenerative gas-furnaces consisting of a box-like casing, a lining of refractory material for said casing, a 45 transverse partition dividing the casing into two chambers, and blocks extending from one side of the casing to the partition, said partition together with the blocks and refractory lining being supported on plates extending 50 along the edges and across the bottom of the casing, substantially as described.

2. A box-like casing having its lower side open, a horizontal plate fixed to the lower edge of the casing extending on both sides of the 55 lines of the walls of the casing, and a refractory lining for the casing carried on the inwardly-projecting part of said plate, the outwardly-extending portion of the plate having a downwardly-extending annular flange out- 60 side the lines of the walls of the casing, substantially as specified.

3. A reversing-valve for regenerative gas-furnaces consisting of a semicylindrical casing having a partition dividing it into two 65 chambers and open on its lower face, the edges of the openings of the chambers in said

face having downwardly-projecting flanges, and a plate extending around the outside of the casing also having a downwardly-projecting flange, said flange extending downwardly 70 to a greater length than the first-mentioned flange, substantially as specified.

4. A reversing-valve for regenerative gas-furnaces consisting of a casing divided by a transverse partition into two chambers, said 75 chambers being open on their lower face, the edges of each opening being surrounded by a downwardly-projecting flange, a plate extending in an approximately horizontal plane and fixed to the lower portion of the casing, said plate also having a downwardly-projecting flange outside of the first flange, said second flange being circular in form and projecting down to a level below the lower edge of the first flange, substantially as specified. 80

5. The combination of a flue structure for regenerative gas-furnaces provided with four flue-openings, a sealing-pit surrounding said openings and extending between the same, a reversing-valve having a transverse partition dividing it into two chambers open on 90 their lower face, with downwardly-projecting flanges extending around said openings, and a plate fixed to the valve having a second flange extending around the casing, said flanges being constructed to enter the said sealing-pit, substantially as specified. 95

6. The combination of a flue structure having four flues opening into it, a sealing-pit extending around said flue-openings, and sealing-pits of relatively less depth extending around each flue-opening, with a reversing-valve provided with two chambers open on their lower face, the openings from said chambers being provided with downwardly-projecting flanges constructed to enter the shallow sealing-pits and a plate extending around the valve provided with a downwardly-extending flange of greater length than those surrounding the openings of the chambers, said flange 100 being constructed to enter the outer sealing-pit, substantially as specified. 105

7. A reversing-valve for regenerative gas-furnaces, the same consisting of a casing, a framework for said casing, means on the 110 framework connected to the casing for raising the same and a cylinder also carried on the casing having grooves in its interior and a pin on the means connecting the raising means with the casing, constructed to engage said grooves, whereby the casing is given a partial revolution as it is raised or lowered, together with means for causing the pin to traverse the grooves in but a single direction substantially as specified. 115

8. A reversing-valve for regenerative gas-furnaces, the same consisting of a casing, a framework for the same, supporting means for raising said casing at will, a rod connecting the casing to the said means, two members consisting of a pin and a body having 120 grooves, one of said members being attached 125

to said rod and the other member being carried by the framework and engaging the first member, said members serving to partially revolve the casing as it is raised or lowered, together with means for causing the pin to move through the groove in a constant direction, substantially as described.

5 In testimony whereof we have signed our

names to this specification in the presence of two subscribing witnesses.
